(57) **CLAIM**

We claim the ornamental design for a ball socket dust boot, as shown and described.

DESCRIPTION

FIG. 1 is a top isometric view of the ball socket dust boot; FIG. 2 is a bottom isometric view of the ball socket dust boot;

FIG. 3 is a side view of the ball socket dust boot;

FIG. 4 is a top plan view of the ball socket dust boot;

FIG. 5 is a bottom plan view of the ball socket dust boot; and,

FIG. 6 is a cross-sectional side view of the ball socket dust boot taken along the line 6-6 of FIG. 5.

The broken lines rendered in FIG. 1 illustrates the environment of the claimed design and forms no part thereof.

1 Claim, 6 Drawing Sheets
